(57) **CLAIM**

I claim the ornamental design for a cucurbit illuminator, as shown and described.

DESCRIPTION

FIG. 1 is a bottom perspective view of a cucurbit illuminator;

FIG. 2 is a top perspective view of the cucurbit illuminator of FIG. 1;

FIG. 3 is a top plan view thereof;

FIG. 4 is a bottom plan view thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a bottom perspective view of a cucurbit illuminator having a rounded lens portion, in all other aspects identical to the views shown in FIGS. 1-8 above; and,

FIG. 10 is a front elevation view of the cucurbit illuminator having a rounded lens portion, in all other aspects identical to the views shown in FIGS. 2-9 above.

The broken lines shown in the design of the cucurbit illuminator illustrate portion of the article and form no part of the claimed design.

1 Claim, 10 Drawing Sheets
